UNITED STATES PATENT OFFICE.

CHARLES FRANCIS JENKINS, OF WASHINGTON, DISTRICT OF COLUMBIA.

GAS-MOTOR STARTER.

1,003,752.

Specification of Letters Patent. Patented Sept. 19, 1911.

Application filed February 27, 1911. Serial No. 611,081.

To all whom it may concern:

Be it known that I, CHARLES FRANCIS JENKINS, citizen of the United States, residing at Washington, District of Columbia, have invented certain new and useful Improvements in Gas-Motor Starters, of which the following is a specification.

This invention relates to that class of devices known as gas engine starters in which a distributing device is employed for delivering a compressed fluid in succession to the several cylinders of a multiple-cylinder motor, and has for its main object a diminution of the friction and an increase in the effectiveness of the fluid pressure. In these devices two things are essential: (1) close-fitting surfaces between the rotor and stator to prevent undue leakage, and (2) a distributor which will produce the least possible amount of friction therebetween.

It has been found as explained in my application, Serial No. 591,797, that conical surfaces, between the rotor and stator, produce the necessary close fit, when the compressed fluid is applied to the upper surface of the rotor, but that the angle of the rotor contact with the stator must be such that there is no such wedging effect as will produce adhesion of the contacting surfaces. However, the more or less large surface in contact, subject to the pressure of the compressed fluid, produces undesirable friction between the adjacent contacting surfaces. This works more harm at high than at lower pressures, that is, for starting the motor the applied fluid pressure is less effective at high than at low pressure, which seems paradoxical, but is explained, as follows:

Probably ninety-five per cent. of all automobiles are, at this time, fitted with four-cylinder, four-cycle motors. Such motors have their cranks set at one hundred and eighty degrees and for that reason develop "dead-centers" every half revolution. The fly-wheel is, therefore, depended upon to carry the cranks over these dead-centers. Again, the fly-wheel in coming to rest after the igniting current is cut off, oscillates two or three times (after the last revolution) and finally stops about half way between the opening of the exhaust and the next dead-center. This leaves a permissible space of about three-sixteenths of a revolution only, or three-thirty-seconds of a cycle, in which the compressed fluid may be applied through the distributor (after due allowance has

been made for "lap" of the ports) to start the motor. In this three-sixteenths revolution the compressed fluid must be applied so effectively as to carry the crank past the next dead-center against the compression of the next firing cylinder. After the pressure is cut off the force that carries the crank past the dead-center is the momentum developed in the fly-wheel by this sudden impulse on the piston. The impulse is applied in but three-sixteenths of the revolution while the friction applies not only during this three-sixteenths but for the whole time, while only the momentum of the fly-wheel acts during the time the fluid is cut off.

It has been found that the momentum developed in the fly-wheel under the impulse of the compressed fluid does not increase in the same proportion as the friction for the remaining part of the revolution and that therefore a hundred and twenty-five pounds of pressure rarely produces as good a result as a hundred pounds. If, however, an increased impulse could be given the fly-wheel with a correspondingly increased momentum, without the development of additional friction, the wheel should travel through the remainder of the revolution at a very much higher speed, producing a correspondingly increased reliability. This conclusion has been found correct, and its application accomplished by the invention of the distributor, described in this specification and the accompanying drawings, which has been found in practice to increase the reliability and certainty of the device more than a hundred per cent.

The device consists of a stationary body having a plurality of ports therein and a tapered seat for the rotor, said rotor resting on a ball-bearing, which latter takes the load of the applied compressed fluid, as shown in the drawings, in which—

Figure 1 is a top view of the distributor; and Fig. 2 a sectional view on the line *x—y* of Fig. 1.

In both figures like symbols refer to like parts, in which—

A is a body or stationary part of the device; *B* a rotor or revolvable member; *C* a ball-thrust bearing between the rotor and stator; *D* is an opening in the rotor which registers in succession with the ports *E¹*, *E²*, *E³* and *E⁴* of the stator, to distribute a compressed fluid to each of the cylinders of a four-cylinder motor; *F¹*, *F²*, *F³* and *F⁴* are

terminal pipe connections leading one each to each of the cylinders of the motor; G is a lower cap supporting the ball-thrust bearing; H is an upper cap through which the compressed fluid is let into the hollow rotor. The rotor has a depending stem which is attached to any suitable part of the motor to receive synchronous rotation therefrom. This stem, being a depending stem, permits of attachment to the motor without the use of a packed stem. The lower cap G is adjustable longitudinally of the distributor to raise or lower the ball-thrust bearing until it carries the thrust of the applied compressed fluid and relieves the rotor of any undue friction with the walls of the stator although permitting such a close fit as to prevent leakage.

It is quite evident that a hundred and twenty pounds pressure applied to the interior of the rotor B would create a friction between the contacting surfaces of the rotor and stator such that it would be impossible to turn the rotor at all unless this pressure were supported by a suitable bearing, *e. g.*, the ball-thrust bearing shown. And yet it is possible to so adjust this thrust bearing that the contacting surfaces between the rotor and stator are gas tight. This adjustment having been made, the operation of the device is entirely obvious to those skilled in this art and it is believed no detailed explanation is required.

The use of the phrase "ball bearing or ball-thrust bearing" in this specification and the claims is intended to mean any rolling-surface bearing and is not intended to be confined strictly to spheres.

What I claim, therefore, is—

1. In distributing valve apparatus, for fluids under pressure, the combination with a valve casing having interiorly converging lateral walls and a series of lateral discharge openings, of a hollow valve revolvably fitting in said casing, open at its larger

end and provided with a lateral port in position to register with said openings in succession as the valve rotates, a cap closing the larger end of said casing and provided with an inlet for supplying fluid under pressure to the interior of the valve, an unyielding antifriction bearing at the smaller end of the valve, to resist the inward thrust of the fluid upon the valve, and means for rotating the valve. 55

2. The combination with an interiorly conical valve casing having a series of lateral discharge openings in the same plane, of a cup-like valve normally covering with its lateral wall all said openings and provided with a lateral port in said plane a ball bearing device unyieldingly limiting the movement of the valve toward the smaller end of the casing, a closure for the larger end of the casing forming an abutment for fluid within the valve when the fluid urges the valve toward the smaller end of the casing, means for supplying fluid under pressure within the valve, and means for rotating the valve. 60

3. The combination with the one-piece, internally conical valve casing having a series of equidistant lateral passages, in the same plane, all opening outward on the same side of the casing, of a cup-like valve revolvably fitting within said casing and provided with a lateral port in said plane, an unyielding adjustable ball bearing device forming a stop for the smaller end of the valve, a removable closure for the larger end of the casing provided with a passage for the admission of fluid under pressure, and means for rotating the valve. 70 75

In testimony whereof I have affixed my signature in presence of two witnesses.

CHARLES FRANCIS JENKINS.
